Patented Apr. 18, 1916.

UNITED STATES PATENT OFFICE.

MILTON W. LEHMAN, OF NEW YORK, N. Y.

TOY SUBMARINE BOAT.

1,180,053.

Specification of Letters Patent. Patented Apr. 18, 1916.

Application filed November 2, 1915. Serial No. 59,197.

To all whom it may concern:

Be it known that I, MILTON W. LEHMAN, a citizen of the United States, and a resident of the city of New York, borough of Brooklyn, in the county of Kings and State of New York, have invented a new and Improved Toy Submarine Boat, of which the following is a full, clear, and exact description.

10 This invention relates to games and toys and has particular reference to toy boats.

Among the objects of the invention is to provide a cheap and attractive imitation of a submarine boat, the same being designed 15 to submerge automatically and then subsequently rise to and float upon the surface by a continuation of the same automatic operation.

Another object of the invention is to provide a simple toy or contrivance adapted to 20 teach boys and others a number of the common or well established principles of physics, having reference particularly to the buoyancy of water and the action of propellers upon navigable vessels.

With the foregoing and other objects in view, the invention consists in the arrangement and combination of parts hereinafter described and claimed, and while the invention is not restricted to the exact details 30 of construction disclosed herein, still for the purpose of illustrating a practical embodiment thereof reference is had to the accompanying drawings, in which like reference characters designate the same parts in the several views, and in which—

Figure 1 is a side elevation of a preferred form of the invention indicating in full lines the position and direction of movement of the submarine toward the bottom and indicating in dotted lines a subsequent movement of the same vessel toward the surface; Fig. 2 is a side elevation indicating the position of the boat just at the 40 moment it reaches the bottom; Fig. 3 is a bottom plan view of the boat; and Fig. 4 is a front elevation of the sinker.

The hull or body 10 of the boat is preferably made to simulate as much as possible 45 the form of a standard submarine boat hav-

ing a tapered or pointed bow 11 and stern 12. The keel of the boat consists preferably of a flat plate-like member 13 of sufficient weight to maintain the boat in upright position in the water whether submerged or not. 55 This plate 13 is fitted adjustably by any suitable means along the bottom of the hull so as to vary its position with respect to the bow and stern and thereby making it possible to vary the angles at which the 60 boat will submerge or rise in the water. For convenience and simplicity of construction I provide a saw kerf 14 lengthwise of the bottom of the hull and of a width corresponding to the thickness of the plate 13 65 and at any point along which the plate may be fixed and held by friction.

At 15 I show a sinker made preferably of metal and adapted to be carried by the boat while it is to be submerged and connected in such a manner as to be automatically released from the boat when the bottom is reached, thereby setting the boat free to float or rise toward the surface of the water. The sinker may be connected to the 70 boat in this manner by any suitable means, but the means I prefer for this purpose comprises a hook or nose 16 formed on the lower front corner or point of the keel plate 13. The sinker may be formed with a loop 75 or eye 17 for temporary connection with the hook 16. The hook being directed forwardly and approximately parallel with the longitudinal axis of the boat, and the sinker being hooked upon the same loosely and the 80 weight of the sinker being sufficient to overcome the buoyant action upon the boat, when the boat is placed into the water with the sinker attached and the boat is then released, it will immediately sink into and beneath the water due to the gravitation of 85 the sinker. The lower end of the sinker striking upon the bottom will cause the sinker to be automatically released from the hook 16, setting the boat free to float to 90 the surface of the water. The sinker, therefore, serves to automatically sink the boat 95 and provide for its re-floating in a continuous operation.

The keel plate 13 and sinker carried there- 100

by being connected to the hull preferably at approximately the middle position longitudinally thereof, the tendency of the device is to sink directly to the bottom so far as has 5 yet been described, and when the sinker is detached, the tendency likewise is for the boat to rise approximately directly upwardly. I provide, however, suitable means to cause the boat to glide forwardly along 10 the water at any desired angle with respect to the horizontal, such forward gliding being caused by the weight under the influence of the rudder. The rudder preferably consists of a flat plate 18 of tin or similar metal 15 carried by the stern 12 and lying in a horizontal plane coinciding substantially with the longitudinal axis of the hull. This rudder, therefore, resists at the stern the downward movement of the boat under the action 20 of the sinker, thereby causing the nose or bow of the boat to be directed downwardly at an angle determined by the relative weight or longitudinal position of the sinker and keel plate. In any event, the lower 25 point or edge 15' of the sinker reaches downwardly below the level of any part of the hull and always strikes the bottom first. This lower edge 15' is preferably comparatively sharp, thereby insuring that the sinker 30 will not stand upright on the bottom but will tilt forwardly due to the movement of the boat. The momentum, however, of the boat in a downward and forward direction will cause a relative lifting of the loop portion 35 17 clearing it from the hook 16 and causing the upper portion of the sinker to tilt forwardly as shown in Fig. 2, thereby setting free the boat. The buoyancy of the water will then cause the boat to rise toward 40 the surface when again the rudder 18 retarding such buoyant action at the stern end of the boat will cause the nose or bow to project upwardly and the combined action of buoyancy and the effect of the rudder 45 will cause the movement to be forward as well as upward, as shown in dotted lines.

For convenience of recovery of the sinker from the bottom of the body of water, I attach a light flexible line 19 to it and the 50 other end of the line to the stern end of the boat.

A device made in accordance with the description herein affords a great deal of amusement to boys and others interested in 55 submarine navigation, and the principles upon which it operates are of an instructive nature.

The device may be manufactured and sold at very low cost, and the same is not likely 60 to get out of order with the exercise of ordinary care.

I claim:—

1. In a toy submarine boat, the combination of a hull, a keel plate for the hull and

adjustable longitudinally therealong, and 65 means to cause the boat to sink, said sinking means being automatically detachable when engaging the bottom, permitting the boat to rise.

2. In a toy submarine boat, the combination of a hull, a keel piece secured to the bottom thereof, and a sinker detachably connected to the keel piece, said sinker being adapted to disconnect automatically when reaching the lower limit of movement, thereby setting the boat free to float to the top of the water.

3. In a toy submarine boat, the combination of a hull, a keel piece secured to the middle portion thereof and having a forwardly projecting nose, and a sinker looped detachably upon and carried by said nose and serving to cause the boat to submerge toward the bottom of the water, said sinker being automatically detached from the nose 85 when coming to rest upon the bottom, permitting the boat to float to the surface of the water.

4. In a toy submarine boat, the combination of a hull, means to maintain the hull 90 upright in all positions of movement in or through the water, a sinker carried by the last mentioned means and automatically releasable therefrom when the lowermost point of submergence is reached, and means to 95 cause the boat to submerge downwardly along an inclined path and subsequently rise toward the surface along an upwardly inclined path.

5. In a toy submarine boat, the combination of a hull, means to sink the hull to the bottom of the water, said sinking means being automatically detached when the bottom is reached setting the boat free to rise to the surface of the water, and a rudder secured to the hull and serving to cause the boat to move downwardly along an inclined path and subsequently rise along an upwardly inclined path.

6. In a toy submarine boat, the combination of a hull, a keel piece secured to the bottom thereof, said keel piece having a forwardly projecting nose, a sinker supported loosely upon said nose and serving to cause the boat to sink toward the bottom of the 115 water, said sinker being automatically detached from the nose when the bottom is reached, setting the boat free to rise to the surface, and a rudder secured in fixed position in a transverse plane corresponding 120 to the longitudinal axis of the hull and serving to cause the boat to move in a downwardly or upwardly inclined path.

7. In a toy submarine boat, the combination of a hull, a keel piece carried thereby, 125 a sinker detachably connected to the keel piece and becoming detached therefrom automatically when the boat reaches the

bottom of the water, and a flexible line connecting the sinker to the hull.

8. In a toy submarine boat, the combination of a hull, means to maintain the hull in upright position whether at or below the surface of the water, and means to cause the boat to sink, said sinking means

being automatically detached when reaching the bottom of the water, thereby permitting the boat to rise to the surface.

MILTON W. LEHMAN.
